[57] CLAIM

The ornamental design for a combined perfume bottle and closure, as shown and described.

DESCRIPTION

FIG. 1 is a front elevational view of a combined perfume bottle and closure showing my new design,

FIG. 2 is a rear elevational view thereof,
 FIG. 3 is a right side elevational view thereof,
 FIG. 4 is a left side elevational view thereof,
 FIG. 5 is a top plan view thereof,
 FIG. 6 is a bottom plan view thereof;
 FIG. 7 is a front elevational view of an alternative embodiment of a combined perfume bottle and closure showing my new design,
 FIG. 8 is a rear elevational view thereof,
 FIG. 9 is a right side elevational view thereof,
 FIG. 10 is a left side elevational view thereof,
 FIG. 11 is a top plan view thereof,
 FIG. 12 is a bottom plan view thereof;
 FIG. 13 is a front elevational view of an alternative embodiment of a combined perfume bottle and closure showing my new design,
 FIG. 14 is a rear elevational view thereof,
 FIG. 15 is a right side elevational view thereof,
 FIG. 16 is a left side elevational view thereof,
 FIG. 17 is a top plan view thereof,
 FIG. 18 is a bottom plan view thereof;
 FIG. 19 is a front elevational view of an alternative embodiment of a combined perfume bottle and closure showing my new design,
 FIG. 20 is a rear elevational view thereof,
 FIG. 21 is a right side elevational view thereof,
 FIG. 22 is a left side elevational view thereof,
 FIG. 23 is a top plan view thereof,
 FIG. 24 is a bottom plan view thereof;
 FIG. 25 is a front elevational view of an alternative embodiment of a combined perfume bottle and closure showing my new design (FIGS. 2-6 provide additional views of this embodiment);
 FIG. 26 is a front elevational view of an alternative embodiment of a combined perfume bottle and closure showing my new design (FIGS. 8-12 provide additional views of this embodiment);
 FIG. 27 is a front elevational view of an alternative embodiment of a combined perfume bottle and closure showing my new design (FIGS. 14-18 provide additional views of this embodiment); and,
 FIG. 28 is a front elevational view of an alternative embodiment of a combined perfume bottle and closure showing my new design (FIGS. 20-24 provide additional views of this embodiment).
